UNITED STATES PATENT OFFICE

140,621

DESIGN FOR A TOY WHEELBARROW

Howard D. Allen, Los Angeles, Calif.

Application August 7, 1944, Serial No. 114,793

Term of patent 14 years

(Cl. D34—15)

To all whom it may concern:

Be it known that I, Howard D. Allen, a citizen of the United States, residing at 4620 West Avenue 41, in the county of Los Angeles and the State of California, have invented a new, original, and ornamental Design for a Toy Wheelbarrow, of which the following is a specification, reference being had to the accompanying drawing, forming part thereof.

Fig. 1 is a side elevational view of a toy wheelbarrow showing my new design; and

Fig. 2 is a front elevational view thereof.

I claim:

The ornamental design for a toy wheelbarrow, as shown.

HOWARD D. ALLEN.
